MOTORS COMPANY, OF NEW YORK, N. Y., A CORPORATION OF DELAWARE

INTERNAL COMBUSTION ENGINE

Application filed October 27, 1928. Serial No. 315,517.

The accompanying drawings illustrate the preferred form of the invention; though it is to be understood that the invention is not limited to the exact details of construction shown and described, as it is obvious that various modifications thereof within the scope of the claims will occur to persons skilled in the art.

In the drawings:

10 Fig. 1 is a side elevation of an internal combustion engine of the marine type, showing the invention applied thereto, certain parts being broken away and others being shown in section;

15 Fig. 2 is a front elevation of the engine shown in Fig. 1 with certain parts broken away;

Fig. 3 is a sectional view of the oil filler cap;

20 Figs. 4, 5 and 6 are sectional views of the breather cap; and

25 Figs. 7 and 8 are views showing a modified form of elbow or separator used with the invention.

30 This invention relates generally to internal combustion engines and has particular reference to means for increasing the speed and power thereof.

One of the main objects of the present invention is the provision of means operative in accordance with the speed of the engine for feeding air at a pressure above atmospheric to the mixing chamber of a carburetor.

35 Another object of the invention is to provide means associated with the fly wheel of an internal combustion engine for delivering air at a pressure above atmospheric to the mixing chamber of a carburetor whereby to permit the fuel mixture to be delivered under pressure to the intake manifold of an internal combustion engine so as to largely eliminate the possibility of backfiring into the carburetor by dissipation due to the pressure of the fuel mixture.

40 A further object of the invention is the provision of means for leading vapors from the crank case of the engine to the intake manifold and thence into the engine to be burned, whereby to prevent said vapors from

50 circulating through the atmosphere and becoming obnoxious.

A still further object of the invention is to provide means for delivering fuel mixture to the cylinders of an internal combustion engine at a pressure above normal so as to increase the speed and power of the engine.

55 Other objects and advantages of this invention will be apparent from the following description taken with the accompanying drawings in which A indicates generally an internal combustion engine of the marine type having a plurality of cylinders; in the instance shown, the engine is a six cylinder one.

60 The cylinder block is shown at 2, the head at 4, and the removable head cap is shown at 6, the latter being detachably secured to the block by fastenings such as screw bolts 8 or the like.

65 For supplying lubricating oil to the engine, a filling port 10 is provided which is normally closed by a cap 12, hingedly secured to the head cap 6 as at 14, and normally retained in seated position on the filling port by a retaining clamp 16. The crank case is indicated at 18.

70 The engine shown in the drawings is of the marine type, as heretofore mentioned, and includes two separate and distinct intake manifolds assemblies, 20 and 22, respectively, which are preferably jacketed as shown, whereby they may be cooled by water circulating through the engine and through the manifolds by conduits 24 leading to and from a reservoir 25. For effecting uniform pressures in the manifolds, the latter are connected by a balance tube 26, and the manifolds are connected to carburetors B and C respectively, having discharge conduits 28 and 30 respectively, in which are the throttle valves controlled for simultaneous actuation by levers 32 connected to an operating rod 34 mounted in brackets 36 secured to the cylinder block. The carburetors B and C are connected to a common source of fuel supply, not shown.

75 Carburetors B and C are shown more or less diagrammatically and the same are provided with mixing chambers 38 and 40 inter-

80

85

90

95

100

posed between the discharge conduits 28 and 30 and the float chambers 39 and 41 respectively, as more clearly shown in Fig. 2. The drawings show the carburetors as formed of separate parts—but obviously they may be cast in one piece as desired; the drawings being for illustrative purposes only.

Secured to the crank shaft (not shown) is a fly wheel 42 provided with teeth 44 for engagement by an electric starter or the like. In the absence of a starter, lever 46 is provided for rotating the fly wheel in an obvious manner, the same being formed for removable attachment to the crank shaft or fly wheel.

The front face of the fly wheel is provided with radial vanes 48 (see Fig. 2) which function to draw atmospheric air into the fly wheel housing 50 through apertures 52 formed in the housing cover 54. The housing 50 is provided with an opening 56 in the rear thereof, defined by a rearwardly extending casting 58, in the form of a boss, and a coupling 60 is secured to the boss 58 by means of suitable fastenings such as screw bolts 62.

Secured to the coupling 60 in any desired manner is a conduit 64, the latter inclining upwardly and having its opposite end secured within a curved coupling 66 by means of a set screw 68 or the like. The coupling 66 is in effect a separator, as hereinafter described, and is provided with a baffle 70 which divides the separator into two passages 72 and 74, respectively. The separator is further provided with a port 76 which is defined by an upwardly extending flange 78 into which the lower end of a breather pipe 80 is secured, the latter extending upwardly adjacent the cap 6 and having a breather 82 secured thereto and in communication with the space 84 within the cap as hereinafter particularly described. The pipe 80 has been termed a breather pipe, but it has a double function. It functions as a breather pipe and also as an aspirating tube or fitting, the function and operation of the tube or pipe 80 being fully described hereinafter.

The lower end of the separator 66 is secured to the inlet 86 of a distributor 88, the latter being preferably a casting of the form shown in Fig. 1, providing oppositely extending conduits 90 and 92 connected respectively to the mixing chambers 38 and 40, heretofore mentioned, as shown at 94 in Fig. 2, whereby to direct air passing through 64, 66 and the conduits 90 and 92 into the mixing chambers to mix with the fuel from the carburetors B and C, respectively. The passages 72 and 74 terminate at the inlet opening of the distributor 88, and said inlet opening provides in effect a mixing chamber 86. It will be apparent that the air from the two passages 72 and 74 will be mixed in this chamber 86 and the crank case vapors which may have been drawn through the

tube 80 into passage 74 will be thoroughly mixed with the air in said mixing chamber 86, thereby eliminating any possibility of a non-uniform mixture of air and vapor being delivered to the respective carburetors. The draft induced in the tube 80 by the suction of the engine draws clean air from the atmosphere unless there is vapor admitted into the fitting 82. If there are crank case vapors in the fitting 82, they are drawn through the tube 80 with the atmospheric air therein and the mixture of atmospheric air and vapor enters the coupling 66 on the side thereof which has the greater radius and where the incoming air through the conduit 64 has the greatest velocity. Since the tube 80 enters the coupling at an angle to the direction in which the air from the conduit 64 is travelling, it will be apparent that there is a suction created in the tube 80 in addition to the suction created by the downward movement of the engine pistons, and the baffle or separator 70 serves only to direct a portion of the incoming air from the conduit 64 and also from the tube 80 straight down on the side nearest the carburetor 40, as shown in the example illustrated in the drawings. The air from passages 72 and 74 mingles in the mixing chamber 86 after it leaves the separator 66, and as only one piston is inducing air into the cylinders at any one time, the air passing through the passage 74 and containing vapor from the tube 80 will mingle with the air in the chamber 86 and cause a uniform mixture to be delivered to the oppositely extending arms 88 and 90 of the distributor.

An important feature of this arrangement is that the air is delivered at uniform pressures to each of the extensions of the distributor. The air passing through the conduit 72 has a shorter path to travel and its velocity would normally be reduced by the sharpness of the curve in its path. While the curve in the conduit 74 is more gradual, it accordingly forms less resistance to the passage of air. This would normally result in the building up of a higher pressure at that part of the mixing chamber 86 which is adjacent the outlet of the conduit 74 than in that part adjacent the outlet of the conduit 72. Such a condition would result in the air being delivered more freely to the branch 90 than to the branch 88, because the higher velocity at the right side of the mixing chamber 86 would cause a clockwise pivoting action about the slower moving portion of air at the left side of the conduit 86. In order to at least partially counteract the tendency of the columns of air 72 and 74 to move at different speeds, the pipe 80 is connected to the faster moving column 74 in such a manner that a part of the velocity of the air in this column is dissipated in ejecting air and crank case vapors from the con-

duit 80. By properly calibrating the size and position of the discharge of conduit 80 into the conduit 74 the velocity of the air in this conduit can be substantially equalized with the volume of air in the conduit 72. 5 From the above it will be seen that the chamber 86 serves not only as a mixing chamber for the air and crank case vapors, but it serves the more important function of forming an inlet capable of delivering air at the same velocity and pressure to each of the carburetors. 10

It will be obvious from the above description that the conduit is acted on by that portion of the incoming air which is at the highest velocity, that is, if the conduit 80 was connected to the conduit 72 the ejector action would be weaker, because it is the normal tendency of air to flow through the conduit 20 at a slower rate.

As shown clearly in Fig. 1, the lower surface or wall of the distributor is pressed upwardly as at 95 substantially opposite the lower end of the baffle 70 to provide oppositely extending curved deflecting surfaces 96 and 98 for distributing the air entering the casting substantially equally to the conduits 90 and 92.

Fig. 1 shows a portion of the engine broken away to disclose the interior of the crank case, cylinder block and the head. A timing chain is indicated at 100, the latter being mounted on the gears 102 and 104; gear 102 being arranged in the cylinder head and mounted on a suitable shaft journaled on a closure cap 106 adjustably secured to the head 4 by means of the bolts 107 which work in suitable slots formed in the cap 106 whereby to provide a means for adjustment of the cap to afford a means for adjusting the timing chain. Just adjacent the upper edge of the cylinder block there is provided an inwardly extending shelf 108 which, when the cylinder head is removed, is adapted to support the gear 102. To remove the head 102, the closure 106 is first removed from the head, which frees the shaft to which gear 102 is secured, thereby permitting the gear to be lowered to the shelf 108 by which it is supported, thus avoiding the necessity of completely removing the gear 102 and the chain 100 when the cylinder head is removed.

This end of the engine provides a passage from the crank case 18 to the interior of the cap 6 for the passage of vapors from the crank case, as will be apparent, and the shelf 108 acts as a baffle to largely prevent the passage of oil which may be entrained in said vapors into the space 84.

The oil filler cap 12 is provided with an opening 110 which permits the admission of atmospheric air into the space 84 where it mixes with the crank case vapors, and the mixture of air and vapors are led into the

breather 82 during the normal breathing action of the engine.

The breather is preferably of the form shown in detail in Figs. 4, 5 and 6, and comprises a tubular body portion 112 into which the upper end of pipe 80 extends; the end of the body portion being provided with an internal annular recess 114 forming a supporting shoulder 116 which seats on the upper end of the pipe 80, whereby to support the breather. 70

The upper end of the body portion is formed with an attaching face 118 provided with an opening 120 so arranged as to lie adjacent a corresponding opening formed in the cap 6, and internally of the upper end of the body portion 112 there is provided an upright baffle 122, the upper end of which is horizontally arranged or flanged as at 124 to provide, in effect, a mixing chamber 126 for the incoming air and crank case vapors. The breather is provided with a head 128 having slots 130 by which additional air is admitted to the mixed air and crank case vapors, the mixture being adapted to be drawn down through the pipe 80, as hereinafter described. 80

As air is forced through the conduit 64 and through the coupling 66, it will be apparent that an aspirating effect is created through the pipe 80 which will serve to draw atmospheric air through the breather; the air passing from 130 through 112 and then into the pipe 80. Through one portion of the fitting 82 the crank case vapors pulsate back and forth due to the normal operation of the engine, in a manner well understood in the art. There is a draft in proportion to the speed of the engine passing through the tube 80 and this draft is always in one direction. In order to prevent the escape of the crank case vapors to the atmosphere, the breather or fitting 82 has been so designed that these crank case vapors will be drawn through chamber 120 into part 112 of the fitting and then down through the tube 80 with the air which is being drawn through said tube 80. Of course, if there are no crank case vapors pulsating through the opening 120 the suction through the tube 80 will draw clean air through the port 130 and admit it to the respective carburetors. However, if there are vapors pulsating through the opening 120 the vapors will be drawn into the tube 80, as just mentioned. From this it will be apparent that the elements 80 and 82 have a double function and that the crank case vapors are prevented from escaping to the atmosphere. 100

Figs. 7 and 8 show a modified form of separator in which a pipe 132 is shown cast as a part of the separator; the inlet end of said pipe being arranged in the upper portion of the intake end of the separator, and the outlet end being arranged so as to discharge into the conduit 90. Attention is called to the fact that the diameter of the pipe 132, especially 110

at its inlet end is approximately one half of the area of the upper half of the intake end of the separator, whereby to provide a construction and arrangement of parts in which substantially equal amounts of air are discharged into the separator.

It is believed that from the above description the operation of the device will be fully apparent to those skilled in the art to which it appertains; but a short résumé of the operation is herein set forth.

With the parts assembled as shown clearly in Fig. 1, when the engine is started the rotation of the fly wheel will cause the vanes 48 to draw atmospheric air through the openings 52 into the housing, from where it passes, due to the rotation of the fly wheel and also because of the normal suction of the engine, through the conduit 64 to the upper end thereof where it is separated by the baffle 70 and is directed downwardly in substantially equal amounts into the distributor and thence the air passes through the conduits 90 and 92 to the mixing chambers 38 and 40 where it is mixed with the fuel from the carburetors and delivered into the manifolds and into the engine cylinders to be burned. It will be obvious that during the operation just described the crank case vapors will be drawn downwardly through the pipe 80 by virtually a siphonic action into the passage 74, from where they pass into the distributor and are burned. Due to the blower action of the fly wheel, it will be apparent that the incoming air is above atmospheric pressure and is mixed with the fuel at such pressure, and the resultant fuel mixture is carried upwardly into the manifolds and into the engine at the valves 134 shown in Fig. 2, at a speed above normal.

It will be obvious that in the conduit 64 the air will be denser or heavier at the upper portion of the upper end; and to effect a substantially equal distribution of air to each carburetor the baffle 70 is arranged in such a manner as to divide the air in the separator 66 so that substantially equal amounts pass through the respective passages 72 and 74 and thus eliminate the tendency of all of the air, or the major portion thereof, to pass to the far side of the separator.

As heretofore mentioned, the air which is drawn through the fly wheel and into the conduit 64 is at a pressure above atmospheric and the pressure depends, of course, largely upon the construction and arrangement of the vanes 48, and it is to be understood that this invention contemplates not only the specific arrangement and construction of vanes such as shown and described in the drawings, but also comprehends the idea of providing a fly wheel which may have vanes arranged in such a manner as to produce any desired pressure of air in the conduit 64.

This depends largely upon conditions re-

quired or desired. In any event, the pressure of the air being above atmospheric will serve to dissipate the flame of a backfire from the engine before it reaches the atmosphere and thus greatly reduce and eliminate the possibility of fire due to such a backfire.

During the operation of an engine, more particularly an engine of the type described and shown, when initially starting the engine a premature ignition of the fuel mixture sometimes occurs. This is dangerous in that sometimes the flame from such premature ignition will pass entirely through the manifolds and carburetors to the atmosphere and set fire to the boat. With the device of the present invention, the fire hazard is appreciably reduced in that, due to the housing and the housing cover, and also the conduit leading to the carburetors, a cushion of air is provided between the atmosphere and the engine into which the flame from a premature ignition is projected; and due to the fact that the housing contains the fly wheel or blower, and further that the housing is provided with a cover, the egress of air from the conduit is retarded to such an extent that the air cushion serves to dissipate the flame from such premature ignition and thus prevent the flame from reaching the atmosphere. It will further be apparent that should the flame reach the fly wheel housing the fly wheel therein and the housing itself being cool, will reduce the temperature to such an extent as to prevent the egress of the flame to the atmosphere. In addition, it can be seen that the tortuous path which the premature ignition must take in reaching the atmosphere is formed by the conduit as well as the fly wheel itself and the latter will serve to effectually and completely break up the premature ignition or the flame therefrom.

During normal operation of the engine a backfire may occur, as is well known, and if such an occurrence takes place the device of the present invention provides an incoming stream of air which is at a pressure above atmospheric and into which the backfire is projected, and it will be apparent that this incoming stream of air will be sufficient to dissipate the backfire; but even should the stream of air not be sufficient, the backfire will be completely broken up by the fly wheel itself in an obvious manner.

What I claim is:

1. In an internal combustion engine, a plurality of carburetors, and means for introducing air under pressure above atmospheric to the carburetors whereby to deliver fuel mixture to the engine at a pressure above atmospheric comprising a distributor connecting said carburetors and provided with a common inlet substantially midway of the ends thereof, a conduit, a blower mounted on and actuated by the crank shaft for deliver-

- ing air under pressure to the conduit, a separator connecting the conduit and distributor, means in said separator for dividing the air injected therein from the conduit to provide a uniform discharge thereof into the common inlet of the distributor, the latter having oppositely extending deflecting surfaces arranged substantially opposite the areas defined by said dividing means whereby substantially equal amounts of air are delivered to each carburetor, and means for balancing the pressure of the fuel mixtures delivered from the carburetors.
2. In an internal combustion engine, a plurality of carburetors, a distributor connecting said carburetors, a conduit, a blower actuated by the crank shaft for delivering air under pressure to the conduit, a coupling connecting the conduit and distributor, and means for leading the crank case vapors to the engine to be burned comprising an aspirating pipe connected to the coupling, a breather secured to the upper end of the pipe, said breather being in communication with the space above the cylinder head of the engine to receive crank case vapors therefrom and said breather having a portion open to the atmosphere to receive air, and a baffle in the coupling for dividing the incoming air substantially equally.
3. In an internal combustion engine, a plurality of carburetors, a distributor connecting said carburetors and provided with oppositely extending arms, a common inlet and oppositely arranged deflecting surfaces arranged opposite the inlet, a conduit, a fly-wheel housing, a fly-wheel therein provided with a plurality of blades for directing air into the conduit at a pressure above atmospheric, a coupling connecting the conduit and distributor at the common inlet, means in the coupling for dividing the air injected therein from the conduit to provide a uniform discharge of air through the common inlet to be separated by the before-mentioned deflecting surfaces, a pipe connected to the coupling, and a breather receiving crank case vapors to be drawn into the pipe by the air passing through the coupling whereby said vapors may be led to the engine to be burned.
4. The combination of an engine provided with a crank case and a plurality of carburetors, an air supply conduit for the carburetors, a conduit for leading crank case vapors to said air supply conduit, and means in the air supply conduit adjacent the junction of said conduits for separating the air to direct substantially equal amounts to each carburetor.
5. In combination with an internal combustion engine provided with a crank case and a plurality of carburetors, an air supply conduit for the carburetors, a conduit for leading crank case vapors to the air supply conduit, and air separating means in said air

supply conduit at substantially the junction of the conduits for reducing the normal increase in the amount of crank case vapors drawn from the crank case and for separating the air in the air supply conduit whereby substantially equal amounts are directed to the respective carburetors, and for preventing aspiration by the full column of air from the vapor conduit.

6. In combination with an internal combustion engine provided with a crank case and a plurality of carburetors, an air supply conduit for the carburetors, means for forcing air through the conduit at a pressure above atmospheric and variable in accordance with the engine speed, an aspirating tube connected with the conduit and through which crank case vapors are drawn by the incoming air through the conduit, and means in the conduit at the junction of the aspirating tube therewith to separate the air whereby substantially equal amounts are supplied to the respective carburetors and for reducing the aspirating effect of the full current of air through the conduit.

7. In combination with an internal combustion engine provided with a crank case and a plurality of carburetors, a main air supply conduit for the carburetors, means for forcing air through said air supply conduit at a pressure above atmospheric and variable in accordance with the engine speed, an aspirating tube connected with the conduit for receiving crank case vapors, a supplementary air inlet for conveying air to the aspirating tube to mix with the crank case vapors, the incoming air through the main air supply conduit serving to draw the additional air and crank case vapors through the aspirating tube, and means in the air supply conduit at the junction of the aspirating tube therewith to separate the air from the main air supply conduit whereby substantially equal amounts thereof are supplied to the respective carburetors and for reducing the aspirating effect of the full current of air through the conduit.

8. In an internal combustion engine, a distributor having a centrally disposed inlet and a pair of oppositely disposed branches, a supply conduit leading to said inlet, an elbow in said conduit, a longitudinally extending baffle dividing the passageway through said elbow into inner and outer parts and means for restricting the flow through the outer part to such an extent as to cause the fluid to be discharged from each of said parts at substantially equal velocities.

9. In an internal combustion engine, a distributor having an inlet and a pair of oppositely extending branches, a conduit for supplying air to said distributor, an elbow in said conduit, a longitudinally extending baffle dividing the passageway through said elbow into inner and outer portions, and a

conduit leading from a chamber of said engine and connected to the outer portion of said passageway.

10. In an internal combustion engine having a plurality of cylinder inlets, a plurality of carburetors, means for introducing fuel mixture to the engine cylinder at a pressure greater than normal comprising a distributor having oppositely extending arms connected to the carburetors, a blower secured to and actuated by the engine crank shaft, a conduit receiving air under pressure from the blower, means connecting the conduit and distributor for directing air under pressure to the latter, means in said directing means for separating the air into a pair of streams, said directing means forming a longer path for the travel of one of said streams and a shorter path for the travel of the other of said parts, and means for introducing additional air to one of said parts, whereby said parts will be delivered to the inlet of said distributor at substantially equal pressure.

11. In an internal combustion engine, a plurality of carburetors, and a supercharger comprising a distributor having oppositely extending arms connected to the carburetors, a fly-wheel mounted on the crank shaft and actuated thereby, a conduit, means formed with said fly-wheel for directing air from the atmosphere to the conduit, and elbow coupling connecting the distributor and conduit, means in said coupling for dividing the air therein into two streams, said dividing means normally tending to cause one of said streams to flow at a higher pressure than the other of said streams, and a passageway for delivering air at substantially atmospheric pressure to one of said streams, whereby the discharge pressures and volume of the two streams are balanced.

12. In an internal combustion engine, a housing, a pair of carburetors, a conduit for supplying air to said carburetors, a bend in said conduit, a longitudinally extending baffle separating the passageway through said bend into inner and outer portions, and a conduit having an air inlet in said housing and an outlet discharging into said outer portion.

In witness whereof I have hereunto set my hand.

ELBERT J. HALL.
